UNITED STATES PATENT OFFICE.

BERNARD W. STRAW, OF MOUNT AIRY, MARYLAND, ASSIGNOR TO STRAW BALLAST DISTRIBUTER CORPORATION, OF WILMINGTON, DELAWARE, A CORPORATION OF DELAWARE.

BALLAST SPREADER.

Application filed July 14, 1926. Serial No. 122,463.

This invention relates to the application of ballast or the like to the roadbed of a railroad and, more particularly, to a receptacle attached to an ordinary railway car or adapted for being adjustably attached to a hopper or other ballast carrying car for receiving ballast therefrom and evenly distributing the same as needed on the roadbed.

The principal object of my invention, generally considered, is the provision of a ballast receiving device formed with one or more doors adapted for providing an accurately graduated opening for distributing ballast along a railroad track, said device being preferably attached to an ordinary railway car or suspended from the sides of the car and extending above the rails and beneath the load containing part of the car.

An object of my invention is the provision of a ballast receiving pan or receptacle preferably elongated and formed with relatively low side walls and one or more apertures in the bottom thereof closed by a sliding door or doors for graduating the flow of ballast therethrough, said device being adapted for transverse positioning with respect to the car beneath a discharge opening therein and preferably spaced slightly above the car supporting rails.

Another object of my invention is the provision of a ballast receiving and spreading device adapted for being positioned beneath a discharge door or doors of a hopper or other ballast receiving car, said device being formed with bottom doors permitting spreading of ballast between and adjacent the rails and having apertured end walls, said apertures being closed by sliding doors for graduating the flow of ballast to either side of the roadbed, and said doors being adapted for manual operation from either side of the device.

A further object of my invention is the provision of a ballast spreading device adapted for being positioned beneath the opening in a hopper or other ballast receiving car and constituting means for receiving and gradually spreading ballast on the road-bed, said device, for that purpose, being provided with an opening in the bottom thereof and a slide for closing one side portion or the other of said opening, whereby the effective

position of said opening may be varied in accordance with the direction of flow of the ballast from the car and sliding doors for covering and uncovering the remaining portion of said opening.

Other objects and advantages of the invention relating to the particular arrangement and combination of the various parts will become apparent as the description proceeds.

Referring to the drawings illustrating my invention, the scope whereof is defined by the appended claims:

Figure 1 is a side elevation of an embodiment of my ballast spreading device suspended from the side walls of the type of car with which it is preferably used.

Figure 2 is a top plan of the form of device shown in Figure 1, the end walls being omitted.

Figure 3 is a fragmentary bottom plan of my ballast spreader.

Figure 4 is an end elevational view of the illustrated embodiment of my invention.

Figure 5 is a sectional view on the line 5-5 of Figure 2 looking in the direction of the arrows.

Figure 6 is a longitudinal sectional view of a portion of a car with my ballast spreader in position with respect thereto, said spreader being shown in section on the line 6-6 of Figure 2.

Figure 7 is a fragmentary sectional view on the line 7-7 of Figure 4 looking in the direction of the arrows.

Referring to the drawings in detail, like parts being designated by like reference characters, my ballast spreader 1 is preferably suspended so as to extend transversely beneath the body of a car 2 and more specifically so as to directly underlie a discharge opening 3 thereof, said opening 3, in the present instance, being adapted for closure by a door 4 adapted for operation in any desired manner. Although my invention is shown applied to a hopper type of car provided with a plurality of hoppers discharging longitudinally of the car in opposite directions yet I do not wish to be limited to such a showing as, if desired, my spreader may be used with flat bottom cars having discharging openings therein or with other

forms of cars adapted for carrying ballast and discharging it from the bottoms or sides thereof.

My ballast spreading device preferably 5 comprises a floor plate 5 provided with sides 6, which may be formed by the upright flanges of longitudinal stiffening angle irons 7. Said floor is preferably rigidified by a plurality of transverse reinforcements 8 and 10 formed with central openings 9 providing a substantially continuous opening which extends the full length of the spreading device except for the spaces connected by the reinforcements 8 and portions of the floor 15 plate of corresponding width.

In order to provide for varying the effective position of the openings 9, so that the spreader may be used most efficiently when it underlies a hopper discharging either to 20 the right or to the left, a slide 10 is preferably provided which, in the present instance, is adapted to cover substantially one-third of the area of the openings and which may be formed continuous from the one extreme end 25 stiffener 8 to the other. Said slide is preferably guided at its ends by being received between guiding strips 11 and the floor plate 5 of the device and may be prevented from longitudinal movement with respect to said 30 guiding strips 11 by having abutment pieces 12 riveted or otherwise connected to engage said guiding portions as most clearly shown in Figure 2. The closure strip 10, as shown most clearly in Figure 6, is preferably positioned 35 adjacent the hopper opening 3 of the car so that the effective discharge opening is disposed very close to the door 4 when the spreading device is normally positioned with respect to the car. It will thus be seen that 40 an adjustable opening is provided for the gradual spreading of ballast therethrough, said opening not only being adjustable in size on account of the sliding doors to be hereinafter described, but being adjustable in 45 position because of the sliding closure member 10 so that the discharge opening is normally disposed adjacent the hopper or other door of the car where the ballast or other material may be directly discharged toward it.

The openings remaining in the floor 5 of the spreading device, after the closure plate 10 has been positioned in accordance with the hopper with which the device is employed, may be closed by a single sliding manually operated door, if desired, but in accordance with the present embodiment of my invention, I have shown these openings closed by a central or intermediate sliding door 13 and end sliding doors 14 and 15, respectively. The intermediate or central sliding door 13 preferably extends between the intermediate stiffeners 16 which, in the present embodiment, normally substantially 65 overlie the rails of the track on which the as-

sociated car is operated. Said door 13, therefore, serves for spreading ballast between the rails of the track and the doors 14 and 15 serve for spreading ballast beyond or outside the rails of the track. The door 13 preferably 70 slides between the floor plate 5, the central stiffener 8 and the intermediate stiffeners 16, fillet means being provided between the floor plate 5 and the intermediate stiffeners 16 to prevent binding of the door therebetween. Undesired endwise movement of the door is 75 prevented and the operation thereof facilitated by rollers or other anti-friction means 17 rolling on the intermediate stiffeners 16 and preferably journaled on studs 18 provided 80 on the underside of the sliding door 13.

Any desired manually operable means may be provided for actuating the sliding door 13 and, in the present embodiment, I have shown levers 19 pivotally mounted on studs 85 or pins 20 provided on the central stiffener 8 and prevented from undesired removal therefrom by cotters or the like 21. The connection between the levers 19 and the sliding door is, in the present instance, made by a U shaped strip 22 connected to the bottom of the door 13 at either end thereof and surrounding the adjacent portion of the respective lever 19 while engaging the same loosely enough to permit the desired angling motion of the lever with respect thereto. The levers 19 extend beyond the ends of the spreading device 1 and are preferably reduced in size to provide convenient hand holds 23 for opening and closing said door. It will be obvious that, if both of the levers 19 are operated simultaneously in the same direction, for example, by a railroad employee positioned at either side of the car adjacent the end of the spreader, the door 13 will be opened or closed to the desired degree. If it is desired to distribute ballast adjacent only one rail or to a greater degree adjacent one rail and between both rails, one 90 of the employees will operate his lever 19 to a greater extent to thereby cause the door 13 to angle and provide a greater opening at one end thereof than at the other, a sufficient clearance between the rollers 17 and the adjacent braces 16 being provided for the 95 purpose.

The end openings 9, in the present instance, are closed by the individual separately operable doors 14 and 15, said doors being similarly guided between the floor plate 5 and the braces 8 and 16, although the outer ends of said doors may rest directly on the operating levers 24 and 25, which levers in turn are pivoted to the floor plate 5 by means of pins 26 and 27 as illustrated particularly 100 in Figures 2 and 5. In order to prevent binding between the operating levers and the floor plate 5, spacing plates 28 are positioned between said levers and floor plate. The connection between the levers and spreader 105 110

doors 14 and 15, in accordance with the present embodiment, involves studs or pins 29 and 30 on the doors 14 and 15, respectively engaging in corresponding slots 31 and 32 in said levers, the lower ends of each of said studs 29 and 30, beneath the levers, being preferably provided with a retaining cotter 33 and a washer 34.

From the foregoing, it will be clear that I have provided means for graduating the flow of ballast or other material received from an associated car upon my spreading device either between the rails or outside of the rails. By virtue of the levers 24 and 25 overlying the operating levers 19 for the central sliding door, there is no interference between said levers and the central door may be operated simultaneously with or independently of the outer or end doors. If greater leverage is desired for operating the sliding doors, the same may be secured by applying a piece of pipe of suitable size (not shown) over the hand holds, as will be understood.

End walls 35 are preferably provided for my spreading device, said walls preferably comprising end plates 36 and angular braces or stiffening means 37, leaving therebetween an opening 38 which is preferably closed by a vertically sliding door 39. Guiding slots between the stiffening means 37 and the plate 36 are provided by having filler strips 40 positioned between said angular members 37 and the plates 36 as most clearly shown in Figure 7.

The end walls 35 are preferably adjustably connected with the main pan shaped portion of the spreading device by pins 41 extending through outer strap portions 42 on the end walls, a selected aperture 43 in the adjacent side wall 6 and a corresponding aperture 44 in the angular stiffening portion 37 at each side of each end wall of the device. This mode of connection between the end walls and the bottom and side walls permits flexibility allowing application to cars of various sizes. The pins 41 are preferably prevented from loss by being connected to the adjacent portion of the corresponding end wall by chains 45.

For operating the sliding doors 39, a link 46 is pivotally connected adjacent a lower edge thereof as indicated at 47 and the upper end of said link is pivoted to an operating lever 48 as indicated at 49. Said operating lever is adapted for operation from either side of the device so that the operator may follow the spreading device as the car is moved along the track and raise or lower the door 39 to the desired degree. In the present embodiment, the fulcrum means for the lever 48 comprises removable pins 50 adapted for insertion in corresponding apertures 51 in the lever and 52 in the angular bracing member 37 of the end wall and it will be noted that

each wall is provided with a pivot pin 50 preferably connected by a chain 53 to the angular stiffener 37 of the end wall, whereby said lever may be fulcrumed adjacent either end thereof and operated from the other end as will be understood.

My ballast receiving and spreading device is preferably connected to an associated hopper or other ballast containing car by means of a hook 54 at either end thereof and an adjustable chain passing through an aperture 55 in the end plate 36 as shown most clearly in Figure 1, said hooks being preferably positioned over the respective top edges of the car at each side thereof to hold the device directly beneath a hopper or other opening 3 with one side wall 6 engaging the usual angular stiffener 56 below the hopper and the other side wall serving to limit the opening of the hopper door 4, thereby preventing loss of material over the side thereof. Of course, before connection with the car, the slide 10 is positioned so that the effective opening lies most nearly in line with the flow of ballast from the hopper as shown most clearly in Figure 6.

The operation of my device is as follows: After hooking on to the car, as illustrated in Figures 1 and 6, with the floor of the device so positioned that the door 4 will open and permit the discharge of ballast from the car, the slide 10 is positioned as indicated and all of the bottom and end sliding doors in the device are closed. The door 4 of the car is then opened permitting ballast, or other material desired to be distributed along the track, to flow into the spreading device. The doors 9, 14, 15 and 39 are then opened to the desired degree and closed as desired by employees who walk beside the car as the same is moved along the track to thereby evenly distribute ballast or the like, as needed, over the roadbed. It will be apparent that, when using a device of this character, only so much of the ballast as is needed is dropped on the roadbed thereby greatly reducing the amount of manual labor now required to be expended in ballasting track, and consequently effecting large savings in the cost of such work. In other words, one of the very expensive features of ballast application, that is, the spreading and distributing of large piles of ballast dropped on the roadbed, as has heretofore been necessary when using hopper and other ballast carrying cars, is eliminated.

When one of the pockets of the hopper car has discharged its ballast and the latter has been distributed, the ballast spreading device is shifted so as to be brought into proper operating relation with the next hopper from which the ballast is to be discharged. To effect this shifting of the ballast spreader the pins 41 by which the end walls 35 are flexibly attached to the bottom of the spreader are withdrawn, thus permitting said bottom por-

tion to be slid transversely of the car so as to withdraw it from beneath the discharge hopper. The bottom section of the spreader can then be positioned beneath the pocket it is desired to discharge, after which the supporting hooks 54 may be slid along the top edges of the sides of the car until the end walls 35 of the device are in alinement with the ends of the bottom section of the pan. The pins 41 are then replaced and the free ends of the chains are adjusted to support the spreader in the desired position, as shown in Fig. 1.

Although I have shown my device as separate means adapted for receiving ballast or the like from a regular hopper or other rail-way car and distributing the same, as needed, on the roadbed, yet unless otherwise claimed, I do not wish to be restricted to such a showing as I may embody my device permanently as part of a car, so that the same forms part or the whole of a car bottom, or other portion thereof, and serves for distributing ballast directly from the body of the car. It is also to be understood that the term granular is herein employed in a broad rather than in a restricted sense and includes ballast and lump material generally.

Having now described my invention, I claim:

30. 1. In combination, a car formed with a body for holding granular material, and means removably positioned beneath said body for receiving said material, said means being formed with a door adapted for gradual 35 operation to release said material as needed for spreading it beneath said car.

2. In combination, a hopper car formed with a door for discharging ballast therefrom and detachable means positioned beneath said 40 door for receiving ballast, said means being provided with a door adapted to be gradually opened or closed for allowing ballast to be distributed as needed.

3. In combination, a car formed with a hopper and a door for discharging ballast or the like from said hopper to the roadbed beneath the car and means movable with the car and positioned beneath the door of said hopper adapted for receiving material discharged 50 from said car, said means being provided with doors adapted to provide adjustable openings for spreading material along the roadbed where needed.

4. In combination, a car formed with a 55 door adapted to discharge granular material therefrom and a pan adapted to normally underlie said door and be held between the same and rails supporting said car, said pan being formed with sides for retaining said material 60 and a plurality of slidable doors in the bottom thereof, one of said doors being adapted to graduate the flow of material to the road bed between said rails and another of said doors permitting a graduated flow of material to the road bed outside of said rails.

5. In combination, a car formed with a door in the bottom thereof for discharging material therefrom and a material receiving device suspended from the car and normally underlying said door and held in spaced relation with respect to the car supporting rails, said device being provided with bottom doors for spreading material adjacent the rails and side doors for spreading material beyond the rails.

70. 6. In combination, a car formed with a dumping door for discharging ballast or the like, and a ballast receiving pan suspended from the sides of the car and underlying said door, said pan being formed with relatively low sides and a longitudinal discharge opening in the bottom thereof, said opening being closable by slidable doors adapted for graduating the opening provided for spreading ballast therethrough.

80. 7. In combination, a hopper car formed with a door for discharging ballast therefrom and a detachable pan shaped device suspended beneath said door and extending transversely of the car, said device being provided with low transversely extending side walls and relatively high adjustably positioned end walls, said end walls being provided with vertically movable sliding doors for discharging ballast to either side of the car.

85. 8. In combination, a car formed with a door at the bottom thereof for discharging ballast or the like to the roadbed beneath the car and an elongated pan shaped device extending transversely of the car beneath the body thereof and adapted for receiving ballast from the body of the car, said device being formed with side walls and end walls, said end walls being provided with slidable doors therein alternatively adapted for operation from either side of the device.

90. 9. In combination, a car formed with a door adapted to discharge granular material therefrom and a pan like device normally suspended beneath said door between the same and the rails supporting the car, said device being formed with side walls and an opening at the bottom thereof, and means for varying the effective position of said opening depending on the direction of flow of material from the car, said means comprising a slide adapted to close one side portion or the other of said opening and sliding doors adapted to cover or uncover the remaining portion of said opening.

110. 10. In combination, a car formed with a door at the bottom thereof for discharging material therefrom and a material receiving device suspended from the car, normally underlying said door and held in spaced relation above the car supporting rails, said device being provided with an opening at the bottom thereof closed by doors for varying the effective area of said opening for spreading ballast along the track, one of said doors

- being adapted to spread ballast between said rails and another being adapted to spread ballast outside of said rails, and independent operating means for each of said doors.
5. 11. In combination, a car formed with a door for discharging granular material, a device for receiving and spreading said material and means attached to said device adapted to hook over the sides of the car and suspend the same in adjusted position between the discharge door and rails supporting said car.
12. A ballast receiving and spreading device comprising a floor portion adapted to extend transversely over a railroad track beneath a car thereon, an elongated opening in the bottom of said device, sliding doors adapted to graduate the size of said opening for spreading ballast therethrough and manually operable means for adjusting the positions of said doors.
13. A ballast receiving and spreading device comprising a floor portion adapted to be positioned transversely of a hopper car beneath a discharge door thereof, said device being formed with relatively low side walls and relatively high end walls adapted for adjustment with respect to the floor portion of the device, said end walls being apertured and provided with doors for discharging ballast from either end of the device.
14. A ballast receiving and spreading device comprising an elongated pan shaped member adapted for extending transversely of a car beneath the body thereof, said device being formed with side walls and end walls, said end walls being apertured and said apertures being closed by vertically slideable doors; and means for operating said doors comprising a lever adapted for operation from either end thereof, whereby said doors may be opened and closed from either side of the device.
15. A ballast receiving and spreading device comprising a pan like element adapted for suspension beneath a discharge door of a car and above the rails supporting said car, said device being provided with side walls and having an opening in its bottom and means for varying the effective position of said opening depending on the direction of flow of ballast from the car, said means comprising a slide adapted to close one side portion or the other of said opening and sliding doors adapted to cover or uncover the remaining portion of said opening.
16. A ballast receiving and spreading device adapted for suspension from a car and normally underlying a discharge door thereof and positioned above the car supporting rails, said device being provided with an opening in the bottom thereof closed by doors for varying the flow of ballast therethrough, one of said doors being adapted to spread ballast between the rails and another being adapted to spread ballast outside of said rails, and means for independently operating each of said doors.
17. A ballast spreader comprising a receptacle adapted for receiving and spreading ballast and means attached to said device adapted to hook on to the sides of an associated car to suspend the same in adjusted position between a discharge door thereof and rails supporting said car.
18. A detachable device for application to a railway car, said device having manually operable doors and being positioned at the discharge outlet of a car to selectively control the flow of lading from the car to any portion of an underlying roadbed section, said doors being movable independently of the door for normally closing said discharge outlet of the car.
19. In combination, a railway car adapted to hold granular material and to discharge the same by gravity, and means removably positioned beneath said car for receiving material therefrom, said means being adapted independent of the rate of movement of the car to graduate the flow of material from said car as desired for spreading the same therebelow.
20. In combination, a car formed with a door for discharging material therefrom and a material-receiving device positioned beneath said door, said device being provided with side walls and end walls, said end walls being provided with doors for discharging material from the car.
21. In combination, a railway car formed with a door for discharging granular material, and a device movable with the car and independent of the door for receiving and spreading said material, said device being positioned between the car body and the track rails.
22. A material spreading device for detachable application to a railway car, said device comprising a floor portion adapted to extend beneath the car, an elongated opening in the bottom of said device, doors adapted to graduate the size of said opening for spreading material therethrough and means for adjusting the positions of said doors.
23. A device detachably positioned at the discharge outlet of a railway car to selectively control the flow of lading from the car, said device extending transversely of the car and projecting beyond the track rails and including a manually operable door.
24. In combination, a car formed with door openings and having doors for the discharge of granular lading, and means positioned adjacent at least one of said doors and adapted to receive granular material from said door opening, said means including manually operable means to discharge said granular material as desired.
25. A ballast spreader comprising a recep-

tacle adapted to be secured adjacent a regular discharge opening of a gondola car, said spreader having manually operable means for selectively distributing the lading to any portion of the road bed.

26. A ballast spreader for gondola cars comprising a trough shaped receptacle, means formed in said receptacle for distributing ballast, and separate manually operable means adapted to control the flow of ballast through said first named means as desired.

27. A ballast spreader for gondola cars, said spreader comprising a trough-like receptacle supported beneath said car in position to receive ballast from a regular discharge opening of said car, and means carried by said receptacle and adapted to control the flow of ballast from said receptacle so as to deliver it to the road bed between the rails or outside of the rails as desired.

28. In combination, a car, a device detachable from said car and movable with the car for distributing material therefrom, said device being provided with means for selectively distributing said material to the road bed between the track rails and outside of said rails as desired.

29. A device adapted to be positioned at the discharge outlet of a railway car and adapted to control the depositing of ballast or the like from said car, said device being a separate unit from said car and involving a plurality of relatively movable members affording a discharge opening of adjustable size through which said ballast is discharged by gravity.

30. The method of handling ballast which consists of depositing the ballast through a door of a railway car into a trough-like receptacle and causing the ballast to flow from said receptacle to the track as desired.

31. In combination, a railway car body provided with an opening through which granular material is adapted to be discharged by gravity, a door for the opening, and means disposed in the path of material discharged from said opening for controllably varying the amount of said material delivered to the roadbed between the rails and outside the rails.

32. In combination, a railway car body provided with an opening through which granular material is adapted to be discharged by gravity, a door for the opening, and means independent of the extent of opening of the door for controlling at will the proportion of said material delivered to the roadbed between the track rails and the proportion of said material delivered to the roadbed outside said rails.

33. In combination, a railway car body provided with an opening through which granular material is adapted to be discharged by gravity, a door for the opening, and means independent of the extent of opening of the

door for adjustably diverting said material to the roadbed between the rails or outside the rails at will.

34. In combination, a railway car body provided with an opening through which granular material is adapted to be discharged by gravity, a door for the opening, and means disposed in the path of material discharged from said opening adapted to deliver said material coincidently to the roadbed between the rails and outside the rails at both sides of the track and also adapted to prevent at will the delivery of said material between the rails or at the side of the track outside the rails.

35. In combination, a railway car body having an opening through which granular material is adapted to be discharged, and means for controlling the discharge of material through said opening, said means being adapted to arrest said discharge at will and also being adapted to cause the discharged material to be selectively delivered either between the track rails or outside the rails or coincidently between and outside said rails.

36. In combination, a railway car body provided with an opening through which granular material is adapted to be discharged by gravity, a door for the opening, said door being movable to open position under the influence of gravity, and means for varying the amount of material delivered to the roadbed when said door is open.

37. In combination, a railway car body provided with an opening through which granular material is adapted to be discharged by gravity, a door for the opening, said door being movable to open position under the influence of gravity, and means for selectively delivering the discharged material either between the track rails or outside said rails.

38. In combination, a railway car body having a hopper provided with an opening through which granular material is adapted to discharge by gravity, a door for the opening, and means for distributing to the roadbed the material discharged through the opening of the hopper, the door being movable independently of said means, and said means serving to permit the amount of material delivered to the roadbed to be varied at will.

39. In combination, a car formed with a body for holding granular material, a door for preventing discharge of said material from the body, and means positioned beneath the body for receiving said material when said door is open, said means having a discharge opening and a door therefor, whereby the material received by said means may be released and delivered as desired to the roadbed between the rails.

40. In combination, a car having an opening for discharging ballast or the like, a door for closing the opening, and ballast receiving means movable with the car and posi-

tioned to receive the ballast discharged through said opening, said means being provided with a ballast discharging bottom opening and including means whereby the effective area of said bottom opening may be varied independently of the movement of said door.

41. In combination, a car having an opening for discharging ballast or the like, a door for closing the opening, and means for receiving the material discharged through said opening when the door is open, said means being positioned below said opening and providing between the track rails a ballast discharge opening whose effective area is adjustable independently of the position of the door.

42. A ballast receiving and spreading device adapted to be positioned below a discharge opening of a railway car and to be movable along the track rails with the car, said device being formed with a bottom portion through which the ballast may be discharged and being provided with door means serving to control the delivery of ballast between the rails and the delivery of ballast outside said rails.

43. In combination, a railway car body provided with an opening through which granular material is adapted to be discharged by gravity, a door for the opening, and means disposed in the path of material discharged from said opening for receiving said material, said means having its ends projecting outwardly beyond the track rails and being provided with a bottom, side walls, and end walls, at least one of said end walls being formed with an opening and having a door for controlling the delivery of said material to the roadbed outside of the track rails.

44. A ballast spreading device adapted to be positioned between the discharge opening of a railway car and the track rails by which the car is carried, said device being formed with a bottom, side walls, and end walls, and having one or more doors permitting delivery of ballast to the road bed.

45. A ballast spreading device adapted to be positioned between the discharge outlet of a railway car and the track rails by which the car is carried, said device projecting at its ends beyond the track rails and being provided with a bottom and with side walls and end walls projecting upwardly therefrom, said bottom being adapted to extend transversely of the car in a plane substantially parallel to that of the tops of the track rails, and said device being provided with means for permitting ballast to be discharged therefrom.

46. In combination, a railway car body provided with a hopper having a slope sheet forming the floor of said hopper, a door for the discharge opening of the hopper and a ballast spreading device for receiving ballast

discharged from the hopper when the door is opened, said device being adapted at will to permit the delivery of ballast to the roadbed or to prevent its delivery thereto, and being provided with side walls and end walls, one of the side walls being adapted to overlap the outer face of said door when the latter is opened, and one of the side walls being adapted to extend beneath said slope sheet of the hopper.

47. In combination, a railway car body provided with an opening for the discharge of granular material, and means interposed between said opening and the track rails for independently controlling the amount of material deposited between the rails and the amount deposited outside the rails.

48. In combination, a railway car body provided with an opening for the discharge of granular material, and a device adapted to deliver said material to the roadbed between the rails and outside of the rails, said device including means for independently controlling the delivery of material outside of each rail of the track, and independent means for controlling the deposit of material between the rails.

49. In combination, a railway car body provided with an opening for the discharge of granular material, a door for the opening, a device positioned between said opening and the track rails for receiving said material and delivering it to the roadbed, said device extending from beneath the car outwardly beyond the track and including a bottom and upwardly extending side flanges, and also being provided with a door for permitting deposit of the material outside of the track rails, said door when the device is operatively associated with the car being disposed outwardly of the adjacent track rail.

50. In combination, a railway car body provided with an opening for the discharge of granular material, and means positioned between said opening and the track rails for receiving said material and delivering it to the roadbed, said means comprising a bottom section and upwardly extending end sections, at least one of said end sections being detachably connected to the bottom section.

51. In combination, a railway car body provided with an opening for discharging granular material, and means for depositing said material to the roadbed between the track rails, said means being adapted to vary the amount so deposited and to vary the amount deposited adjacent one rail as compared with the amount deposited adjacent the other rail.

52. In combination, a railway car body having an opening for the discharge of granular material, a door for said opening, a ballast spreading device for receiving said material when the door is open, said device extending transversely of the car and projecting at its ends beyond the track rails and being pro-

vided with a door permitting the material to be discharged between the rails, the portion of said device which extends from one track rail to the other being disposed wholly above the tops of said rails.

53. In combination, a railway car body having an opening for the discharge of granular material, and means for receiving the discharged material and delivering it to the roadbed, said means being formed with an outlet opening and a door therefor capable of angular movement substantially in its own plane.

54. A ballast spreading device comprising a pan member provided with a bottom and upwardly extending side walls and having an opening in said bottom, a door for closing said opening, and a plurality of operating means for moving said door, said means being respectively operable from opposite ends of said device.

55. A ballast spreading device comprising a pan member having a bottom and upwardly extending side walls, said bottom being formed to discharge ballast to the roadbed of a railway track, and being provided with a plurality of doors for controlling the discharge through said bottom, each of said doors being formed with an operating handle, said handles being spaced from each other so as to operate in substantially parallel planes.

56. A ballast spreading device comprising a pan adapted to extend transversely across the rails of a railway track and having a floor plate and side walls, said floor plate being formed with an opening adapted to permit delivery of ballast between the rails of a railway track, the said opening being provided with a door adapted to slide beneath said floor plate, and said device having means whereby the door may be operated from the side of the track during the operation of spreading ballast.

57. A ballast spreading device comprising a pan adapted to extend transversely across the rails of a railway track and having a floor plate and side walls, said floor plate being formed with door openings adapted to permit delivery of ballast to the underlying roadbed, the said openings being respectively provided with independently movable doors mounted to slide beneath said floor plate, said device being provided with means whereby the said doors may be operated from the side of the track during the operation of spreading ballast.

58. A ballast spreading device adapted to extend transversely across the rails of a railway track and to deliver ballast between the rails and outside of said rails, said device being formed with a pan like bottom member and end walls, said end walls being flexibly connected to the bottom member.

59. In combination, a railway car having an opening for the discharge of ballast or the

like, and a ballast spreading device to receive ballast discharged through said opening and deliver it to the roadbed, said device including a pan member having a floor plate provided with an opening permitting the discharge of ballast, a door disposed below said floor plate for controlling the discharge of ballast through said opening, supporting plates for said door extending beneath the latter, and means for maintaining said supporting plates in spaced relation to the floor plate.

60. In combination, a railway car having an opening for the discharge of ballast or the like, a ballast spreading device adapted to receive ballast discharged through said opening and deliver it to the roadbed, and means for suspending said device from the car, the device including a pan member and end members, the end members being pivotally connected to the pan member and connected to said means for suspending the device from the car.

61. In combination, a railway car body adapted to carry lading, such as ballast, said body having an opening therein, means for closing said opening, means associated with said opening for receiving ballast discharged through the latter, said last named means having one or more openings therein, and means for controlling, in a predetermined manner, the discharge of ballast through said last named opening or openings.

62. In combination, a hopper car having an opening therein, a closure member for said opening, means operatively associated with said car adjacent said opening for receiving material such as ballast discharged through the opening, said means having a plurality of openings therein, and manually operable closure members for said last named openings.

63. In combination, a hopper car of the type embodying a discharge opening and a closure member for said opening, and means operatively associated with said hopper car for distributing ballast, said means being provided with one or more openings, and means for adjustably closing said last named opening, or openings, to control the discharge of ballast onto a track ballast cross-section.

64. In combination, a car body structure having an opening therein, a closure member for said opening, means operatively associated with said structure adjacent said opening for receiving ballast or the like discharged from said body, said means having one or more openings therein, and closure members for said last named opening or openings.

65. In combination, a railway car having an opening for the discharge of ballast or the like, and a ballast spreading device interposed between said opening and the roadbed, said device being adapted to deliver ballast to the

roadbed between the rails on which the car is supported and comprising a plurality of members which are movable relatively to control the delivery of ballast to the roadbed between said rails.

66. In combination, a railway car having an opening for the discharge of ballast or the like, and a ballast spreading device extending transversely of the car for receiving ballast discharged through said opening and delivering it to the roadbed, said device including a pan member having a floor affording an opening permitting ballast to be delivered to the roadbed between the rails on which the car is supported and provided with a flange projecting upwardly above said floor to check the flow of ballast across the latter.

67. In combination, a railway car having an opening for the discharge of ballast or the like and a door for closing said opening, and a ballast spreading device interposed between said opening and the roadbed and adapted to deliver ballast between the track rails on

which the car is supported, said door being movable independently of said device and the latter having a ballast outlet and being provided with means whereby the effective size of said outlet may be varied.

68. In combination, a railway car having an opening permitting the discharge of ballast or the like under the influence of gravity, an outwardly opening door for closing said opening, and a ballast distributing pan adapted to receive ballast discharge through said opening, said pan extending transversely of the car and being open at the end to permit the delivery of ballast outwardly beyond a rail of the track upon which the car is supported, and being disposed beneath said discharge opening so as to permit said door to open and being provided with a bottom and with spaced side flanges extending upwardly above said bottom.

In testimony whereof I affix my signature.

BERNARD W. STRAW.
